(57) **CLAIM**

I claim, the ornamental design for a wearable autoinjector, as shown and described.

DESCRIPTION

FIG. 1 is a front, right perspective view of a first embodiment of a wearable autoinjector showing our new design; FIG. 2 is a bottom, right perspective view thereof; FIG. 3 is a front elevation view thereof; FIG. 4 is a rear elevation view thereof; FIG. 5 is a left side view thereof; FIG. 6 is a right side view thereof; FIG. 7 is a top plan view thereof; FIG. 8 is a bottom view thereof;

FIG. 9 is a front, right perspective view of a second embodiment of a wearable autoinjector having surfaces of contrasting color showing our new design;

FIG. 10 is a bottom, right perspective view of the second embodiment;

FIG. 11 is a front elevation view of the second embodiment; FIG. 12 is a rear elevation view of the second embodiment; FIG. 13 is a left side view of the second embodiment; FIG. 14 is a right side view of the second embodiment; FIG. 15 is a top plan view of the second embodiment; and, FIG. 16 is a bottom view of the second embodiment.

The broken lines of even length shown in the drawings illustrate portions of the wearable autoinjector that form no part of the claimed design. The broken lines of uneven length define the boundaries of the claimed design.
